US00D824782S

(12) **United States Design Patent** (10) Patent No.: **US D824,782 S**
(45) Date of Patent: **** Aug. 7, 2018**

(54) **WATCH**

(71) Applicant: **MONDAINE WATCH LTD**, Pfäffikon
Sz (CH)

(72) Inventor: **André Bernheim**, Meilen (CH)

(**) Term: **15 Years**

(21) Appl. No.: **35/502,589**

(22) Filed: **Jan. 24, 2017**

(80) **Hague Agreement Data**

Int. Filing Date: **Jan. 24, 2017**

Int. Reg. No.: **DM/094911**

Int. Reg. Date: **Jan. 24, 2017**

Int. Reg. Pub. Date: **Mar. 10, 2017**

(51) **LOC (11) Cl. 10-02**

(52) **U.S. Cl.**

USPC **D10/30**

(58) **Field of Classification Search**

USPC D10/30, 32, 38-39

See application file for complete search history.
